UNITED STATES PATENT OFFICE.

WILLIAM H. KRUMSICK, OF SPOKANE, WASHINGTON.

WRENCH.

1,417,390.

Specification of Letters Patent. Patented May 23, 1922.

Application filed April 18, 1921. Serial No. 462,125.

To all whom it may concern:

Be it known that I, WILLIAM H. KRUMSICK, a citizen of the United States, residing at Spokane, in the county of Spokane and 5 State of Washington, have invented new and useful Improvements in Wrenches, of which the following is a specification.

This invention relates to wrenches and has for an object the provision of a wrench 10 which includes relatively movable jaws after the manner of the usual monkey wrench and which further includes means whereby the wrench may be easily and quickly converted into a socketed wrench.

Another object of the invention is the provision of a wrench of this character wherein the means for operating the movable jaw may also be employed for operating the socketed member of the wrench, the 20 construction permitting of the use of the wrench in restricted spaces.

With the above and other objects in view, the invention further includes the following novel features and details of construction, to be hereinafter more fully described, 25 illustrated in the accompanying drawings and pointed out in the appended claims.

In the drawings:

Figure 1 is a side elevation showing the 30 movable jaw in position and the handle of the wrench rigid.

Figure 2 is a plan view of the same.

Figure 3 is a longitudinal sectional view.

Figure 4 is a transverse section on the 35 line 4-4 of Figure 1.

Figure 5 is a similar view on the line 5-5 of Figure 1.

Figure 6 is a detail perspective view of the movable jaw.

Figure 7 is a side elevation showing the 40 wrench arranged as a socketed wrench and the handle disposed at an angle.

Figure 8 is a longitudinal sectional view of the same.

Figure 9 is a transverse section.

Figure 10 is a detail perspective view of the member which carries the socketed 45 member.

Referring in detail to the drawings, where- 50 in like characters of reference denote cor- responding parts, the wrench is illustrated as including a hollow handle 10, one end of which is provided with a cross sectional rec- tangular portion 11 having one face formed with a longitudinally extending slot 12.

Rotatably mounted within the handle 10

in bearings 13, is a shaft 14, which is pro- 60 vided with a square portion 15 for the recep- tion of a threaded sleeve 16, the threads of which extend from the slot 12 provided in the handle. This sleeve is positioned be- 65 tween one of the bearings 13 and an exter- nally threaded nut 17 which is located within one end of the handle.

Removably and slidably mounted upon the 65 rectangular portion 11 of the handle is a jaw 18, the latter being provided with an opening 19 of rectangular shape for the re- ception of the rectangular portion 11 of the handle and being provided with threads 20 70 for engagement with the threads of the sleeve 16. By rotating the shaft 14, the sleeve 16 will be rotated and the threaded engagement of this sleeve and the jaw 18 will impart a longitudinal sliding movement 75 to the latter. The rigid jaw of the wrench is indicated at 21 and this jaw is provided with an internally threaded opening 22 which receives a threaded extension 23 formed on the handle so that the jaw 23 may 80 be removably secured in position. This construction provides a wrench which may be used both as a nut or pipe wrench, the shape of the jaw 18 permitting of this latter use.

In addition, it is the purpose of the in- 85 vention to provide means whereby the wrench may be used as a socketed wrench. To accomplish this there is provided a rec- tangular sleeve 24 which is designed to re- ceive the rectangular portion 11 of the 90 wrench handle, the jaw 18 first being re- moved to permit of the reception of the sleeve 24. This sleeve is of a length sub- stantially co-extensive with the space be- 95 tween the member 13 and the jaw 21, which is removed for the purpose of applying the sleeve and replaced to hold the said sleeve in position. The sleeve 24 is provided with an extension 25, having an opening 26 there- in and rotatably mounted within this open- 100 ing is a member 27 having a rectangular socket 28 therein. The member 27 is ex- teriorly threaded for engagement with the threads of the sleeve 16 and for this pur- pose, the sleeve 24 is provided with an open- 105 ing 29. By rotating the shaft 14, rotary motion may be imparted to the member 27 through its engagement with the threaded sleeve 16.

Another feature of the wrench is the pro- 110 vision of means whereby it may be used in restricted places and for this purpose the

- shaft 14 is provided with a universal joint 30, while the hollow handle is formed in sections and hinged together at a point adjacent the universal joint as shown at 31. 5 The outer end of the shaft 14 is squared as shown at 32 to receive a suitable tool or implement whereby the shaft may be rotated. By moving the handle upon this hinged portion, the end of the wrench may be inserted 10 in a restricted space, the joint 30 permitting of rotation of the shaft 14 when in this position. In order to hold the handle rigid there is provided an internally threaded sleeve 33 which engages threads 34 and 35 15 formed upon the outer periphery of the handle and when so engaged will bridge the jointed portion of the handle to hold the latter against movement.

The invention is susceptible of various 20 changes in its form, proportions and minor details of construction and the right is herein reserved to make such changes as properly fall within the scope of the appended claims.

25 Having described the invention what is claimed is:—

1. A wrench embodying a handle, means whereby either a longitudinally movable member or a rotatable member may be mounted upon the handle and means engageable with either of said members, whereby the same may be operated.
- 20 30

2. A wrench comprising a handle, means whereby either a longitudinally movable member or a rotatable member may be 35 mounted upon the handle and means located within the handle and engageable with either of said members, whereby the same may be operated.

3. A wrench embodying a handle, means 40 whereby either a movable jaw or a socketed member may be mounted upon the handle and means including a longitudinally disposed threaded shaft engageable with either said jaw or member, whereby the same may 45 be operated.

4. A wrench embodying a handle, means whereby either a longitudinally movable member or a rotatable member may be mounted upon the handle and a common operating element engageable with either of said members, whereby the same may be operated.

5. A wrench comprising a hollow handle, a cross sectional rectangular outer surface 55 provided at one end thereof for the reception of either a movable jaw or a socketed member, a stationary jaw carried by the handle, a threaded shaft located within the hollow handle and engaging either the movable jaw or the socketed member, whereby the same may be operated.

In testimony whereof I affix my signature.

WILLIAM H. KRUMSICK.
